(57) **CLAIM**

The ornamental design for a shelf for wine bottles, as shown and described.

DESCRIPTION

FIG. 1 is a perspective view of the shelf for bottles of the present invention;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof; and,

FIG. 8 is a perspective view thereof showing exemplary use thereof.

The broken lines shown in drawings show portions of the shelf for wine bottles and form no parts of the claimed design.

1 Claim, 5 Drawing Sheets
